Fig. 2.

UNITED STATES PATENT OFFICE

JOSEPH E. CHRISTASTIE, OF ELMIRA, NEW YORK

ELECTRIC STAR

Application filed April 28, 1930. Serial No. 448,095.

This invention relates to ornaments and is particularly adapted for Christmas ornaments.

An object of the invention is to provide an ornament of the character referred to that is very simple in its method of construction, strong, compact and durable, thoroughly reliable for its intended purpose, very pleasing in appearance, and comparatively inexpensive to manufacture.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereto appended.

In the drawings wherein like reference characters denote corresponding parts throughout the several views:—

Figure 1 is a front elevation of the device in accordance with the present invention,

Fig. 2 is a vertical detailed section taken substantially on the line 2—2 of Fig. 1,

Fig. 3 is a fragmentary rear elevation thereof, with the trimmings removed, and

Fig. 4 is a wiring diagram.

In the drawings wherein for the purpose of illustration is shown the preferred embodiment of my invention 5 indicates generally the body portion which is in the configuration of a star. The body portion consists of a flat front wall in the form of a star, preferably a five-pointed star.

Around the edges of the flat front wall 6, there is a depending rim 7 which provides a hollow interior 8 that opens in the rear of the body portion. The points of the star terminate in round ends 9 which also have the depending sides thereon, similar to the sides 7.

The body portions of the round ends 9 at the center thereof are formed with openings 10 around which are depending flanges 11 and seated in the flanged openings are the electric light sockets 12 to receive the electric light bulbs 13. The center of the front wall 6, that is at the center of the star, is likewise

formed with a round opening 14, around which there is a depending flange 15, and in this opening there is also seated an electric light socket 16 supporting the electric light bulb 17.

It is to be understood that there is one electric light socket for each opening on the end of the stars and one electric light socket in the openings 14. Around the outer end of the round end 9 on each star, is secured a rim 18 which encircles the points of the star, and wrapped around this rim 18 is tinsel.

The rim 18 is preferably formed of a round piece of wire. The portion 5 is preferably formed of tin or any other suitable metal. The outer face of the front wall 6 and the outer side of the depending walls 7 are coated with glue and covered with artificial snow. If one coating does not serve the purpose, then two or three coatings thereof may be made.

Furthermore, it is to be understood that while the preferred embodiment of the invention uses imitation snow, the metallic parts thereof may be painted any desired color.

For lighting the star in accordance with the present invention, the conventional eight socket series of electric light bulbs 21 may be used having the required voltage of the current used, and six of the sockets will be used for lighting the star, while the two extra sockets may be used for other purposes, such as in the corners of windows in event the star is used for a window ornament at Christmas time.

The wiring diagram is clearly shown in Fig. 4 of the drawings, and it is believed is self-explanatory. It will be seen by referring to Fig. 4, that the sockets are in series. To facilitate the hanging of the star on any desired point, a loop of wire or cord 22 may be anchored to the wire rim 18 for the purpose of supporting the body portion.

The present embodiment of the invention has been disclosed in considerable detail merely for the purpose of exemplification since in actual practice it attains the features of advantage enumerated as desirable in the statement of the invention and the above description.

It is to be understood that by describing

in detail herein any particular form, structure, or arrangement, it is not intended to limit the invention beyond the terms of the several claims, or the requirements of the prior art.

Having thus described my invention, what I claim as new is:—

1. An ornament of the character described comprising a rigid body portion in the shape

10 of a star, said body portion formed of a flat front wall having rounded apertured portions on the end of the points of the star, and a depending side wall continuous with the front wall and rounded portion, the center 15 of the front wall formed with an opening, and electric light bulbs mounted in the apertures at the center of the body portion and the rounded apertured portions at the ends of the points of the star.

20 2. An ornament of the character described comprising a rigid body portion in the shape of a star, said body portion formed of a flat front wall having rounded apertured portions on the end of the points of the star, a 25 depending side wall continuous with the front wall and rounded portion, the center of the front wall formed with an opening, electric light bulbs mounted in the apertures at the center of the body portion and the rounded 30 apertured portions at the ends of the points of the star, said electric light bulbs electrically connected in series.

35 3. An ornament of the character described comprising a rigid body portion in the shape of a star, said body portion formed of a flat front wall having rounded apertured portions on the end of the points of the star, a depending side wall continuous with the front wall and rounded portion, the center of the 40 front wall formed with an opening, electric light bulbs mounted in the apertures at the center of the body portion and the rounded apertured portions at the ends of the points of the star, said electric light bulbs electrically 45 connected in series, and depending flanges about the apertures to grip the sockets of the electric bulb.

4. An ornament of the character described comprising a rigid body portion in the shape 50 of a star, said body portion formed of a flat front wall having rounded apertured portions on the end of the points of the star, a depending side wall continuous with the front wall and rounded portion, the center 55 of the front wall formed with an opening, electric light bulbs mounted in the apertures at the center of the body portion and the rounded apertured portions at the ends of the points of the star, said electric light bulbs 60 electrically connected in series, depending flanges about the apertures to grip the sockets of the electric bulb, and outer face of the front wall and the outside of the depending wall coated with decorative material.

65 5. An ornament of the character described

comprising a rigid body portion in the shape of a star, said body portion formed of a flat front wall having rounded apertured portions on the end of the points of the star, a depending side wall continuous with the front wall and rounded portion, the center of the front wall formed with an opening, electric light bulbs mounted in the apertures at the center of the body portion and the rounded apertured portions at the ends of the points of the star, said electric light bulbs electrically connected in series, depending flanges about the apertures to grip the sockets of the electric bulb, the outer face of the front wall and the outside of the depending wall coated with decorative material, and a continuous rim about the peripheries of the rounded portions for supporting tinsel wrapped thereabout, and means engageable with the rim for hanging the star in upright position.

In testimony whereof I affix my signature.

JOSEPH EUGENE CHRISTASTIE
